UNITED STATES PATENT OFFICE.

HENRY L. PITMAN, OF PINEVILLE, KENTUCKY.

BUFFER-BRAKE FOR MOTOR-DRIVEN SEWING-MACHINES.

1,052,690.

Specification of Letters Patent. Patented Feb. 11, 1913.

Application filed April 4, 1912. Serial No. 688,405.

To all whom it may concern:

Be it known that I, HENRY L. PITMAN, a citizen of the United States, residing at Pineville, in the county of Bell and State of Kentucky, have invented certain new and useful Improvements in Buffer-Brakes for Motor-Driven Sewing-Machines; and I do hereby declare the following to be a full, clear, and exact description of the invention, such as will enable others skilled in the art to which it appertains to make and use the same, reference being had to the accompanying drawings, and to the letters and figures of reference marked thereon, which 10 form a part of this specification.

This invention relates to new and useful improvements in buffer brake mechanism, especially adapted for use in connection with sewing machines and the object in view is 20 to produce a simple and efficient means whereby the operator of the machine may cause the speed of the machine to be slackened by simply pressing down upon a resilient rod positioned underneath the hand of 25 the operator as it would naturally rest while holding the work to the machine.

The invention consists of a simple and efficient device of this character which is 30 illustrated in the accompanying drawings, in which:—

Figure 1 is a perspective view showing the application of the invention to a sewing machine, and Fig. 2 is a detail perspective view of the brake removed from the 35 machine.

Reference now being had to the details of the drawings by letter, A designates the machine table and B the machine of the usual construction and C the usual hand or 40 fly wheel.

A rod, designated by letter D, is journaled in a suitable bearing E and has one end upwardly bent and curved, forming an arm F with a buffer brake G secured thereto 45 which, as the shaft D is rocked, is adapted

to be thrown frictionally against the wheel C. Said rod is preferably of a resilient material and is curved as at H and one end is pivotally mounted in a bearing K. It will be noted upon reference to Fig. 1 that the 50 curved part of said rod is upwardly bowed and positioned so that the hand of the operator sitting at the machine will naturally rest upon the rod and, when it is desired to slacken the speed of the machine for 55 any purpose, a slight pressure of the wrist or hand of the operator normally resting upon the rod, may cause the arm F to swing laterally under the buffer brake applied to the fly wheel, thus checking the speed of the 60 machine and, at the same time, the operator's hands are at liberty to manipulate the work being operated upon. When pressure is relieved from the bowed portion H of the rod, the latter returns to its normal position 65 and the buffer brake is thrown from contact with the fly wheel.

By the provision of a device as shown and described, it will be observed that an efficient means is afforded for regulating the speed 70 of a machine without the operator having to stop and remove one hand from the work to grasp the wheel for any purpose as is customary with machines of the usual construction.

What I claim to be new is:—

In combination with a sewing machine table, a fly wheel, a rock shaft and bearings in which the same is journaled, said rock shaft having a resilient bowed portion, a brake 80 upon the shaft, said shaft adapted to rock in its bearings as the bowed portion is flexed by pressure being applied thereto, as set forth.

In testimony whereof I hereunto affix my 85 signature in the presence of two witnesses.

HENRY L. PITMAN.
